CLAIM

The ornamental design for an oil distributor, as shown and described.

DESCRIPTION

FIG. 1 is a top, front right side perspective view of an oil distributor, especially for distribution of oil to the bearings of a vacuum pump;

FIG. 2 is a bottom, rear left side perspective view thereof; FIG. 3 is an inverted left side elevational view thereof;

FIG. 4 is a bottom view thereof;

FIG. 5 is a front elevational view thereof;

FIG. 6 is a right side elevational view thereof;

FIG. 7 is a rear elevational view thereof; and,

FIG. 8 is a top plan view thereof.
